GRAPHICAL RECORDER

Francis L. Moseley, Pasadena, and Richard M. Kemplin,
Altadena, Calif., assignors, by mesne assignments, to
Hewlett-Packard Company, Palo Alto, Calif., a corpora-
tion of California

Filed Feb. 4, 1963, Ser. No. 73,420

Term of patent 14 years

(Cl. D26—14)

Fig. 1.

Fig. 2.

Fig. 3.

Fig. 4.Fig. 5.FIG. 1 is a perspective view of a graphical recorder with a particular portion thereof in an extended position showing our new design;

FIG. 2 is a side elevational view of the graphical recorder as shown in FIG. 1;

FIG. 3 is a rear elevational view thereof;

FIG. 4 is a perspective view of the graphical recorder of FIGS. 1-3 showing said particular portion thereof in a retracted position; and

FIG. 5 is a side elevational view of the graphical recorder as shown in FIG. 4.

The essential features of the design reside in the portions shown in full lines.

We claim:

The ornamental design for a graphical recorder, as shown and described.
